UNITED STATES PATENT OFFICE.

ARTIIUR W. WALKER, OF MALDEN, MASSACHUSETTS.

DESIGN FOR A STOVE-LID.

SPECIFICATION forming part of Design No. 22,740, dated August 22, 1893.

Application filed May 29, 1893. Serial No. 475,969. Term of patent 14 years.

To all whom it may concern:

Be it known that I, ARTHUR W. WALKER, a citizen of the United States, residing at Malden, in the county of Middlesex, State of Massachusetts, have invented and produced a new and original Design for a Stove-Lid, of which the following is a specification, reference being had to the accompanying drawings, showing a part thereof.

Figure 1 of the drawings represents a top view of a stove lid showing my design. Fig. 2 is an edge or side view thereof.

The leading feature of my design for a stove lid consists in a cylindrical base *a* having a

flat circular top *b*, and a series of fine curved hair-like corrugations or striations on the upper surface thereof.

I claim—

The design for a stove lid, substantially as herein shown and described.

In testimony whereof I have signed my name to this specification in the presence of two subscribing witnesses.

ARTHUR W. WALKER.
